United States Patent Office.

ELISHA KELLEY, OF LOCUST GROVE, OHIO.

Letters Patent No. 88,790, dated April 13, 1869.

IMPROVEMENT IN CORN-SHELLERS.

The Schedule referred to in these Letters Patent and making part of the same.

To all whom it may concern:

Be it known that I, ELISHA KELLEY, of Locust Grove, Adams county, and State of Ohio, have invented a new and useful Improvement in Corn-Shellers; and I do hereby declare that the following is a full, clear, and exact description of the construction and operation of the same, reference being had to the accompanying drawings, making a part of this specification, in which—

Figure 1 is a vertical section, as indicated by the line *y y*, of fig. 3.

Figure 2 is a side elevation.

Figure 3 is a view in detail, showing the gear-wheel, with fingers.

Figure 4 is a vertical section of the bevelled-gear wheel, giving internal view of the fingers, as indicated by line *x x*, of fig. 3.

Like letters in the different figures of the drawings, indicate like parts.

The nature of my invention consists in the construction of a corn-sheller, with elastic feed-rollers above and below revolving-fingers.

The finger-plates being provided with tongues, working in grooves, and with rubber springs, by means of which the necessary vibrations are secured, to conform to the different-sized ears of corn, and arranged in and revolve with a bevelled-gear wheel.

To enable others skilled in the art to make and use my invention, I will proceed to describe its construction and operation.

A A are rubber rollers, upon proper axles, with gear-wheels *B C* (see dotted lines in fig. 1) arranged above the shellers or fingers, a proper distance apart, to admit an ear of corn.

D D are rubber rollers, similar to rollers *A A*, with gear-wheels *E F*, arranged below the fingers.

H is a bevelled-gear wheel, with a square opening in the centre, *I I I I*, and with slots, or grooves *a a*, as shown by dotted lines, in fig. 3.

K K are fingers or shellers, the plates of which are provided with tongues *c c*, which fit loosely, and operate in grooves *a a*.

L L are rubber springs, arranged between the fingers and the wheel *H*, on rods *d d*, which slide in the holes *e e* in the gear-wheel, as shown in fig. 1.

The driving-wheel *M* is turned by means of crank *N*, and engages pinion *O*, attached to shaft of bevel-

led wheel *P*, which engages and drives bevelled-gear wheel *H*.

Pinion *R*, on the shaft of driving-wheel *M*, engages gear-wheel *S*, which is attached to one end of roller *D*, and drives that roller.

At the other end of the same roller is attached gear-wheel *F*, which engages pinion *G*, which engages gear-wheel *C*, and that wheel engages gear-wheel *B*.

Wheel *F* also engages wheel *E*, and thus both sets of rollers are revolved.

Operation.

The sheller is operated by turning the crank *N*, and the corn is fed, endwise, between the rollers *A A*, which, revolving toward each other, move the ears down between the shellers or fingers *K K*, the revolving motion of which shells the corn from the cob, the ears being held from turning by the rollers, and the lower end of the cob is caught between the lower rollers, and, by them is drawn entirely through the sheller.

The fingers open and close, to conform to the different sizes of the ears of corn, by means of the tongues on the finger-plates working in the grooves, and by means of the rubber springs, as described.

I contemplate that a proper hopper may be attached at the top, to conduct the ears of corn to the rollers in the proper position to be conveyed into the shellers or fingers.

The rollers above and below, as described, serve the two useful purposes of feeding the corn into and through the shellers, and of holding the ears from turning while the corn is being shelled, which, heretofore, had to be done altogether by hand.

Claims.

Having thus fully described my invention, what I claim therein as new, and desire to secure by Letters Patent, is—

The elastic rollers *A A* and *D D*, in combination with the fingers or shellers *K K*, substantially in the manner and for the purpose as described.

As evidence that I claim the foregoing, I have hereunto set my hand in the presence of two witnesses.

ELISHA KELLEY.

Witnesses:

THOMAS BEAVERS,
M. MCKEEHAN.
